UNITED STATES PATENT OFFICE.

WILLIAM D. BRECKENRIDGE, OF WACO, TEXAS, ASSIGNOR OF ONE-HALF TO J. M. POWERS, JR., OF HOUSTON, TEXAS.

OIL-BURNER.

No. 920,819.

Specification of Letters Patent.

Patented May 4, 1909.

Application filed August 26, 1908. Serial No. 450,292.

To all whom it may concern:

Be it known that I, WILLIAM D. BRECKENRIDGE, a citizen of the United States of America, residing at Waco, in the county of McLennan and State of Texas, have invented certain new and useful Improvements in Oil-Burners, of which the following is such a full, clear, and exact description as will enable others skilled in the art 10 to which it appertains to make and use the same.

My invention relates to improvements in devices for burning refined oil and consists in certain novel features which will be hereinafter first fully described and then particularly pointed out in the claims.

In the annexed drawings, which fully illustrate the invention, Figure 1 is a longitudinal section of my improved burner; Fig. 20 2 is a transverse section of the same taken on the line 2—2 of Fig. 1, and Fig. 3 is a detail perspective view of the diaphragm.

The body, 1, of the burner is mainly of a cylindrical form and is provided with a feed 25 passage, 2, leading up to and communicating with a port, 3, through which the oil from the supply pipe, 4, escapes into an upper chamber, 5, extending longitudinally through the combustion or flame end of the body. 30 The supply pipe, as shown, is screwed into the end of the passage 2 and thereby forms the support for the burner. The port 3 is opened or closed by a needle valve, 6, mounted in the body of the burner and projecting 35 from the supply end of the same. From the ends of the chamber 5, flues, 8, extend downward and then inward toward each other and are provided with jets or flame orifices, 9, in their upper sides near or at their extremities as clearly shown. Within the 40 chamber 5 is formed a longitudinal diaphragm, 10, provided with notches, 11, in its edges at its center.

When it is desired to start the burner, a 45 pan of any convenient size is held under the burner and the needle valve is manipulated to open the port 3 whereupon the oil will flow over the diaphragm and through the notches in the edges thereof after which it 50 flows through the flues 8 to the tips where it escapes through the jets 9 into the pan. As the pan forms no part of my invention, I have not illustrated the same. Any pan can be used and the use of the same is common

to oil burners. The diaphragm is convex 55 on its upper surface so as to direct the oil positively to the sides of the chamber and the notches are at the center of the diaphragm so that the oil will flow to the two jets equally. Oil having overflowed into the 60 pan, as stated, a flame from a match or other source is applied thereto so as to cause combustion of the same, the flow of oil to the burner being temporarily cut off. This initial flame will thoroughly heat up the body 65 of the burner so that the oil fed into the supply chamber thereof will be vaporized and the vapor will burn in a strong steady flame when it issues from the jets.

It will be understood, of course, that the 70 needle valve is closed after the pan is filled for the initial flame. When the initial flame supply has been consumed and the burner is heated, the pan is put aside and the valve is opened to admit a supply of fuel to the ignition ports. The burner body having been heated by the initial flame, the oil entering the burner will now be vaporized and will burn at the ignition ports with a strong 75 steady flame. The needle valve enables the user to adjust the escape of oil into the retort chamber so that it will enter said chamber in very small quantities and consequently will be quickly vaporized. The diaphragm serves to further retard the flow so that any 80 oil that should escape vaporization upon its entrance into the retort chamber will be vaporized before passing to the ignition ports. Furthermore, the diaphragm prevents such fuel passing to the ignition ports except at 85 the center of the burner where the heat is greatest so that vaporization will be complete before the fuel reaches the flame.

The device is very simple in its construction and is efficient in operation, requiring 90 no attention to keep it in a condition of operative cleanliness.

Having thus described my invention, what I claim and desire to secure by Letters-Patent is:—

1. An oil burner having a pair of jets, a chamber having its ends communicating with the respective jets, means for supplying oil to the said chamber, and a deflecting diaphragm within the chamber to retard the 105 flow from the chamber to the jets.

2. An oil burner comprising a retort chamber, a pair of jets below the said cham-

ber, flues leading from the ends of the chamber to the jets, and a diaphragm within the chamber having notches in its edges.

3. An oil burner comprising a body having an admission port and an upwardly extending passage leading to the said port, a valve mounted in the body above the said passage and controlling the port, a retort chamber receiving the oil through the said port, a pair of jets below the said chamber

and communicating with the ends of the same, and a convex diaphragm within the chamber provided with notches in its edges.

In testimony whereof, I have signed this specification in the presence of two subscribing witnesses. 15

WILLIAM D. BRECKENRIDGE.

CHARLES LOWELL HOWARD,
R. W. BISHOP.
